(57) **CLAIM**

We claim the ornamental design for a smart watch, as shown and described.

DESCRIPTION

FIG. 1 is a front perspective view of a smart watch showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom rear perspective view thereof;

FIG. 9 is a cross-sectional view taken along the line of 9-9 in FIG. 2; and,

FIG. 10 is a front perspective view of the smart watch in which a wrist band is provided in dot-dot-dash broken lines to illustrate an example environment.

The dot-dot-dash broken lines illustrated in FIG. 10 are for environmental purposes only and form no part of the claimed design.
